(57) **CLAIM**

The ornamental design for a palm rest, as shown and described.

DESCRIPTION

FIG. 1 is a perspective view of the palm rest design of the present invention;

FIG. 2 is an exploded perspective view thereof; and,

FIG. 3 is a perspective view thereof.

The broken line showing of structural features is included for the purpose of illustrating non-claimed subject matter and forms no part of the claimed design.

1 Claim, 2 Drawing Sheets

FIG. 1

FIG. 2
